UNITED STATES PATENT OFFICE.

GRAY I. MORRISS, OF CHICAGO, ILLINOIS, ASSIGNOR TO RELIANCE DRYING ROOM CO., OF CHICAGO, ILLINOIS, A CORPORATION OF ILLINOIS.

HUMIDITY-CONTROLLING MECHANISM FOR DRYING-ROOMS.

1,203,236.

Specification of Letters Patent.

Patented Oct. 31, 1916.

Application filed December 13, 1915. Serial No. 66,527.

To all whom it may concern:

Be it known that I, GRAY I. MORRISS, a citizen of the United States, residing at Chicago, in the county of Cook and State of Illinois, have invented certain new and useful Improvements in Humidity-Controlling Mechanism for Drying-Rooms, of which the following is a specification.

This invention relates to a device for automatically controlling the admission of steam to a drying room for maintaining a constant degree of humidity in the atmosphere of the room.

In the drying of certain articles, as, for instance, varnished or enameled ware, it is desirable to maintain a predetermined degree of humidity in the room in order to secure the best results. It has been found that if the atmosphere is allowed to become too dry there is a tendency to dry and harden the exterior surface of the varnish or enamel before the underlying coats of varnish or enamel are thoroughly dry and hardened, which imperfect drying is termed case hardening, and is very objectionable from every standpoint. By proper regulation of the humidity in the room, this and other objectionable results may be avoided.

The object of the present invention is to provide means for automatically admitting or restricting the admission of the steam utilized for humidifying purposes, in such a manner as to maintain the desired degree of humidity in the room.

In the drawings: Figure 1 is an enlarged detail showing the controlling means inserted in the nozzle of a steam pipe and connected with a standard form of humidity gage; and Fig. 2 is a diagram showing the arrangement of the parts in a drying room.

When installing the controlling mechanism of the present invention, a humidity gage 3 is employed, which may be of any standard suitable formation, and since the interior construction of the gage forms no part of the present invention, it is not deemed necessary to describe it in detail.

The gage is provided with an automatically controlled hand or pointer 4, which moves in conformity with changes in the degree of humidity in the atmosphere, and his pointer is supplemented by a manually adjustable pointer 5, which may be set to any suitable or predetermined position at which it is desired to maintain the humidity

in the room. Thereafter the difference in position between the two pointers will serve to indicate the variation in humidity above or below that which has been determined upon. These features are common in instruments of this class, and need not be further described.

In utilizing the humidity gage for the purposes of the present invention, a circuit wire 6 is provided, which is connected with the manually adjustable hand or pointer 5, and a similar wire 7 leads from the automatically adjustable hand or pointer 4, the parts being suitably insulated so that no circuit can be established until the automatically adjustable hand or pointer has moved to a position coincident with that of the manually adjustable hand or pointer, at which time a contact will be effected and the circuit established. The circuit wires 6 and 7 lead to and connect with a pair of binding posts 8 on the end of an electromagnet 9, having a soft iron core 10 preferably inclosed in a sheath or casing 11 adapted to protect the magnet from the action of the steam. The magnet is suitably mounted or carried within a nozzle 12 of a steam pipe 13 adapted to supply steam under very low pressure to the drying room for humidifying purposes. The nozzle 12 terminates in a conical cap 13 having a discharge orifice 14 designed to admit steam to the interior of the drying room. The cap is provided with an interior ring or bushing 15, which furnishes a valve seat for a flap valve 16 preferably formed of a material which will be sensitive to the attraction of the magnet and at the same time impervious to the action of the steam. The parts are preferably arranged so that the flap valve will fall by gravity, assisted by the magnetic influence, to close the discharge of the nozzle against the discharge of the steam, but will rise under a low steam pressure when the magnetic attraction is removed.

In operation, after the desired humidity for the room has been determined upon, the manually adjustable hand or pointer will be moved to the desired degree, as, for instance, 25°, and the steam will be admitted to the room. As the humidity increases, the automatically adjustable hand or pointer will move until it comes to a position coincident with that of the manually adjustable hand or pointer, at which time a con-

tact will be formed and the circuit closed, which serves to energize the magnet, and with the magnet energized the flap valve will be drawn down against the slight steam pressure and the nozzle closed against the admission of additional steam. So long as the humidity remains at the desired degree, the circuit will be maintained, but when the humidity again begins to fall, the circuit 5 will be broken and the magnet deenergized, allowing the flap valve to rise under the steam pressure, which will admit additional steam until the humidity in the room has been again raised to the desired point. The 10 parts will thus be maintained in practical equilibrium during the drying operation, with the humidity practically constant at all times.

In some cases it may be desirable to vary 20 the humidity in the room during the different stages in the drying operation, but, of course, this can be readily effected by turning the manually operated hand or pointer to different positions as occasion may require. The device is extremely simple in 25 construction and may readily be employed with any one of several well known forms of humidity gages which can be readily adapted to the requirements of the present 30 invention.

Although the invention has been defined as applicable for use in drying rooms, it is obvious that it may be employed in living 35 rooms, store rooms, work rooms or the like, or under any other conditions where it is desirable to regulate and maintain constant degrees of humidity. It is also evident that some humidifying agent other than steam may be used if desired.

40 I claim:

1. In a humidity controlling apparatus, the combination of a humidity gage provided with manually adjustable means adapted to be moved to indicate the desired 45 degree of humidity and means responsive to changes in humidity, circuit wires connecting with each of said means and adapted to establish different circuit conditions when said means are in and out of positions 50 of coincidence, a pipe for admitting a humidifying agent to the space under control, an electromagnet located in said pipe and connected with said circuit wires and adapted to be energized and deenergized by the

making and breaking of a current there-through, and a valve in said pipe adapted to be moved by said magnet to regulate the flow of the humidifying agent through said pipe, substantially as described. 55

2. In humidity controlling apparatus, the combination of a humidity gage provided with a manually adjustable pointer adapted to be moved to a position to indicate the desired degree of humidity, and a pointer responsive to changes in humidity, circuit 60 wires connected with each of said pointers and adapted to afford a closed circuit when said pointers are in a position of coincidence, an electromagnet connected with said circuit wires and adapted to be energized 65 by the closing of said circuit, a pipe within which the magnet is located and adapted to admit a humidifying agent to the space under control, and a flap valve adapted to be drawn to closed position when the magnet is energized, and adapted to be thrown back to open position under the pressure of the humidifying agent when the magnet is deenergized, substantially as described. 70

3. In a humidity controlling apparatus, the combination of a humidity gage provided with a manually adjustable pointer adapted to be moved to a position to indicate the desired degree of humidity, and a pointer responsive to changes in humidity, circuit 75 wires connected with each of said pointers and adapted to afford a closed circuit when said pointers are in a position of coincidence, an electromagnet connected with said circuit wires and adapted to be energized 80 by the closing of said circuit, a pipe within which the electromagnet is mounted, and a flap valve hinged in proximity to the magnet and adapted to be drawn down into closed position by magnetic action and against the pressure of the 85 humidifying agent when the magnet is energized, and adapted to be lifted against gravity and under the pressure of the humidifying agent when the magnet is deenergized for controlling the discharge of the humidifying agent, substantially as described. 90
